UNITED STATES PATENT OFFICE.

SAMUEL A. WIKBERG AND JOHAN WIKBERG, OF EVERSON, WASHINGTON.

DRAFTING INSTRUMENT.

1,227,862.

Specification of Letters Patent.

Patented May 29, 1917.

Application filed June 15, 1916. Serial No. 103,870.

To all whom it may concern:

Be it known that we, SAMUEL A. WIKBERG and JOHAN WIKBERG, subjects of the King of Great Britain, residing at Everson, in the county of Whatcom and State of Washington, have invented a new and useful Drafting Instrument, of which the following is a specification.

This invention has reference to drafting instruments of the character shown and described in Letters Patent No. 1,167,237, granted to us on January 4, 1916, and the object of the invention is to provide an arrangement whereby the operation of the instrument is greatly facilitated, the purpose of the instrument being to provide for the quick and accurate calculation and drawing of a line at any angle and the drawing of arcs and circles, all without the use of T and set squares or compasses.

The instrument described in the aforesaid Letters Patent includes a straight edge diametrically and rotatably mounted within a circular protractor, in turn carried by and slidably arranged along a scale beam, which latter is slidably mounted on and at right angles to a scale stock having means for its attachment to a drawing board.

The general arrangement of the present invention is similar to that described in the aforesaid patent, but the structure is materially refined and improved in various ways permitting a more extended use and definite control of the parts.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings:—

Figure 1 is a plan view of the instrument of the present invention applied to a drafting board.

Fig. 2 is an elevation with some parts broken away, of the structure of Fig. 1 as viewed from the lower side of the showing of Fig. 1.

Fig. 3 is an elevation with some parts

broken away of the structure of Fig. 1 as viewed from the left hand side thereof.

Fig. 4 is a perspective view of a portion of the scale stock and scale beam separated to better show the parts.

Fig. 5 is a detail section through a portion of the protractor showing a means for clamping a movable part of the protractor.

Fig. 6 is a plan view of a portion of the inner ring of the protractor, showing a part of a three-cornered rule and means for holding it in place.

Fig. 7 is an end elevation of the three-cornered rule with a pen or pencil holder mounted thereon.

Fig. 8 is a section similar to that of Fig. 5 but drawn on a larger scale and with the clamping nut in the clamping position.

Fig. 9 is a bottom plan view of a portion of the main or supporting ring of the protractor.

Referring to the drawings there is shown a drafting board 1 having a sheet 2 of drawing paper attached thereto.

At opposite ends of one edge of the board, and lower than the top surface thereof, are brackets 3 fastened thereto by screws 4 or otherwise, and each bracket has an arm 5 extending from the board and provided with an upturned end 6 formed with an eye 7 for the passage of a pivot pin or screw 8. Ordinarily the eye 7 is threaded so that the screw is fixed in the bracket and is provided with an axially located pivot extension 9 entering the corresponding end of a scale stock 10.

In order to extend the usefulness of the scale stock 10, both faces of the latter are provided with scales or graduations 11. The scale stock 10 is usually flat, that is, it is wider than thick, and the pivots engage it in the longitudinal center line of the scale stock, so that in order to utilize one graduated face or the other as desired it is only necessary to turn the scale stock over, but as certain parts carried by the scale stock are not to be reversed they must be removed from the scale stock and replaced thereon so as to have the same relation to the drawing board as before.

Mounted on the scale stock 10 is a block 12 from one side of which extends a frame made up of side arms 13 and connecting yokes 14, together with a bridge 15 at a suitable point. The yokes 14 and bridge 15

serve to space and stiffen the arms 13, and the block, arms, yoke and bridge may, if desired, be all in one piece as a single casting suitable machined for accuracy of operation.

5 The block 12, which may be made of skeleton form for lightness, upstands from the arms 13 in the operative position of the parts, and the yokes 14 and bridge 15 also upstand from the arms 13, which latter are 10 in parallel relation one to the other, and sufficiently spaced to receive the scale stock 10 between them. Each arm 13 has formed on the face presented toward the other arm an elongated tongue 16 adapted to a corresponding longitudinal groove 17 on the appropriate edge of the scale stock 10.

The block 12 with the arms 13 constitute a carrier for a scale beam 18 having scales 19 thereon, which scales may be produced on both sides of the scale beam and the latter is arranged for reversal to permit the utilization of the scale on both faces of the scale beam 18.

The scale stock 10 is, because of the location of the supporting bracket arms 5, at a level below the working surface of the board 1, while the block 12 is sufficiently elevated above the level of the scale stock to carry the scale beam 18 slightly above 30 the working surface of the board 1 and of the sheet of drawing paper 2 carried by the board 1. One end of the scale beam 18 is forked to provide two parallel fingers 20 in line with the scale beam, and 35 these fingers are formed with tongues 21 and grooves 22 fitting corresponding grooves 23 and fitted by corresponding tongues 24 on the upper or top portion of the block 12, the arrangement being such that the tongues 40 and grooves interlock in a manner to firmly hold the scale beam 18 in right angular relation to the scale stock 10, although at a higher level with respect to the working 45 positions of the parts. At the same time 50 the scale beam 18 is capable of longitudinal movement for the connection or disconnection of the forked end of the scale beam with the tongues and grooves of the block 12. By an appropriately close fit the scale beam 18 may be made to hold its position in the block 12 without additional fastening means, although such fastening means may be used if desired. However, it is 55 only at infrequent intervals that the scale beam 18 is removed from, reversed and replaced in the block 12, so that there is little liability of wear and an initially close fit will remain such for a long period of time.

60 Adapted to the scale beam 18 is a slide 25 comprising elongated side bars 26, 27, respectively, connected by yokes 28 and a bridge 29 similar to the bridge 15 before mentioned. The sides 26 and 27 have interior tongues 30 like the tongues 16, and

these tongues engage in longitudinal edge grooves 31 in the scale beam 18, so that not only may the slide 25 be moved lengthwise of the scale beam, but this may be done with either face of the scale beam 18 presented uppermost.

70 Formed on the arm 27 is a circular protractor ring 32 of appropriate size, the ring being thickened at intervals, as shown at 33, so as to rest upon the paper sheet 2.

75 Seated in a channel 34 formed about the body of the protractor ring on the upper surface thereof is a graduated ring 35, the channel 34 being provided with a circumferential rib 36, and the ring 35 being formed with a corresponding circumferential groove 37, and also on its inner periphery formed with a circumferential rabbet 38. Adapted to the inner face of the body ring 32 of the protractor is another 80 ring 39 having a circumferential lip 40 adapted to the rabbet 38.

85 The upper surfaces of the rings 35 and 39 forming part of the protractor have 90 graduations 41, 42, respectively.

95 At an appropriate point the ring 39 carries a clamp screw 43 on the face remote from the graduations 42 and so positioned that its head will bind on the main or body ring 32 of the protractor, thus resisting 100 turning movements of the ring 39 in the protractor. This resistance need be no greater than to prevent accidental movements of the ring without preventing movements of the ring 39 under forces purposely applied.

105 Extending through the ring 39 at another point say, diametrically opposite from the clamp screw 43, is a bolt 44 having a T head 45 seated in an appropriate recess 39a in the ring 39 of the face remote from the graduated face, while the T head engages in a circumferential rabbet 46 formed in the main protractor ring 32 on the under face thereof. The stem of the bolt 44 110 rises through the ring 39 and above the upper surface thereof where it is appropriately threaded for the reception of a recessed thumb nut 47 and a manipulating 115 knob 48. The recess in the thumb nut 47 is designed to receive a coiled spring 49 bearing upon the upper surface of the ring 39 to hold the head 45 of the bolt 44 at all 120 times in the rabbet 46, while the knob 48 is sufficiently spaced from the thumb nut 47 to permit loosening of the latter, so that the ring 39 may be turned as desired, or 125 may be clamped in place by the thumb nut 47.

To hold the ring 35 in adjusted positions 125 there is provided a clamp plate 50 mounted on the arm 27 and overlying the ring 35, the plate 50 being under the control of a thumb screw 51 so that one end of the plate 130 may be made to bear with appropriate pres-

sure upon the ring 35 to hold it in place, and on loosening the thumb nut 51 the pressure on the ring 35 is released so that said ring 35 may be moved to the desired extent.

For fine adjustment a vernier scale 52 in operative relation to the scale on the ring 35 is produced upon the arm 27.

There is also provided a three-cornered rule 53 appropriately scaled, and this rule has pivot supports at its ends in the ring 39, so that one edge of the scale is in a diameter of the ring 39, and by turning the three-cornered rule on its pivot supports 15 any one of the corners of the rule may be brought into the same diameter. To hold the three-cornered rule in adjusted positions it is provided at each end with grooves 54 adapted to receive a finger 55 on one 20 end of a spring plate 56 secured to the corresponding face of the ring 39 by screws 57 or otherwise. A thumb piece 58 on the spring 56 provides for the ready manipulation of the finger 55 and the ring 39 is 25 appropriately recessed, as indicated at 59, to receive the spring 56 and its finger 55 when moved out of a groove 54. One of the pivots of the rule 53 is indicated at 60 in Fig. 6, and it will be understood that the 30 rule has a similar pivot at the opposite end. The three-cornered rule 53 has a longitudinal groove 61 along each face to receive a pin 62 and stem of a thumb screw 63 on opposite sides of a carriage 64 of angular 35 shape adapted to slide along the rule 53. The carriage is provided with a pen or pencil holder 65 for a pen or pencil indicated at 66, so that such pen or pencil may engage the sheet 2 to produce markings thereon, as desired.

Each bridge 15 and 29 has overhanging ribs 67 on opposite sides to enter corresponding grooves 68 in a block 69 capable of moving lengthwise of the bridge, which is 45 in a direction crosswise of the scale stock 10 or scale beam 18, as the case may be. Each block 69 carries an elastic indicator finger 70 secured to the block by a screw 71, and a thumb nut 72, the screw 71 and 50 the stem of the thumb nut 72 passing through elongated slots 73 in the finger 70 to permit of lengthwise adjustment of the finger. At the extremity of the finger 70 remote from the block 69 there is a pointed 55 extension 74 adapted to engage in any one of numerous notches 75 in the graduated faces of the scale stock 10 or scale beam 18, as the case may be, such notches coinciding with the graduations of the scale beam or 60 scale stock. This permits the movement of the slide block 12 with its frame 13 or the slide 25 with the protractor carried thereby lengthwise of the respective parts carrying them with the point 74 of the finger 70 65 positioning the parts as adjusted by en-

gagement in appropriate notches 75, but these notches are sufficiently shallow so as not to resist movements of the parts in adjustment, although normally holding them and indicating to the user when the proper position is reached.

Since the scale stock and scale beam contain numerous graduations different from each other and arranged on opposite sides of each face of the scale stock and scale beam, the capability of the indicator fingers of movement along the respective bridges 15 and 29 crosswise of the scale beam and scale stock permits the use of the indicator fingers in connection with any one of the 80 scales on the respective stock or beam.

The depression of the scale stock with respect to the working face of the drawing board permits the use of the instrument throughout the entire area of the drawing 85 paper without interference of certain parts of the structure with other parts. This greatly extends the range of the instrument over the instrument shown and described in the aforesaid Letters Patent.

The three-cornered rule may be turned about its pivots and reversed in the protractor ring, thus giving the advantage of six scales. The capability of turning the outer graduated ring of the protractor and 95 of clamping it in adjusted positions enables an operator to set the ring at a desired departure from the base line, therefore having the advantage of working with the inner ring from a right angle or zero 100 point, whereby a very considerable amount of figuring is eliminated.

By providing the two rings 35 and 39 of the protractor, one with the English system of measurement and the other with the 105 metric system of measurement, both systems may be used at will.

All scales may have the zero point in the center and be graduated in both directions.

The protractor is made of a suitable material which will not soil the paper and by providing the deeper portions 33 the body of the ring and the rule carried thereby do not engage or rub upon the paper.

What is claimed is:

1. A drafting instrument comprising a scale stock, a scale beam disposed at right angles to the stock and mounted on and movable along the stock at a higher level than the latter, supporting means for the 120 stock located at the ends thereof and adapted to be attached to one side edge of a drafting board with the scale beam above the drafting board, and a protractor device carried by and movable along the scale beam 125 and related thereto to be located above the working surface of a drafting board to which the drafting instrument is attached.

2. A drafting instrument comprising a scale stock, means associated with the scale 130

stock for attaching it to one edge of a drafting board below the level of the working face of the board, a scale beam disposed at right angles to the stock and mounted on and movable therealong at a height above the scale stock to be located above the working surface of a board to which the instrument is applied, and a protractor device mounted on and movable along the scale beam in position to be in elevated relation to the working surface of the drafting board to which the instrument is applied.

3. A drafting instrument comprising a scale stock, means associated with the scale stock for attaching it to one edge of a drafting board below the level of the working face of the board, a scale beam disposed at right angles to the stock and mounted on and movable therealong at a height above the scale stock to be located above the working surface of a board to which the instrument is applied, and a protractor device mounted on and movable along the scale beam in position to be in elevated relation to the working surface of the drafting board to which the instrument is applied, said protractor device being provided with depending portions for contact with drawing paper upon the drawing board, whereby to support the protractor otherwise in elevated relation to the paper on the board to which the instrument is applied.

4. A drafting instrument comprising a scale stock, a scale beam supported by and at right angles to the scale stock and adjustable therealong, a protractor carried by and adjustable along the scale beam, and provided with a rotatable ring, and a rule supported across the rotatable ring with one edge of the rule in a diameter of the ring, said rule having pivotal supports in the ring and said rule being rotatable on its pivotal supports about a longitudinal axis to present any one of a plurality of edges in said diameter of the ring.

5. A drafting instrument comprising a scale stock, a scale beam supported by said scale stock at right angles thereto and adjustable therealong, a rotatable protractor ring and supporting means therefor on and adjustable along the scale beam, and a three-cornered rule supported across and rotatable with the ring with an edge of the rule in a diameter of the ring, said rule having pivotal supports at the ends in the ring for rotation of the rule about its longitudinal pivotal axis for presenting any one of its edges in said diameter of the ring.

6. A drafting instrument comprising a scale stock, a scale beam supported in said scale stock at right angles thereto and adjustable therealong, a rotatable protractor ring and supporting means therefor on and adjustable along the scale beam, and a three-

cornered rule supported across and rotatable with the ring with an edge of the rule in a diameter of the ring, said rule having pivotal supports at the ends in the ring for rotation of the rule about its longitudinal pivotal axis for presenting any one of its edges in said diameter of the ring, said ring and rule having coacting means for releasably locking the rule in different positions of longitudinal rotation.

7. A drafting instrument comprising a scale stock, a scale beam supported at right angles to and adjustable along the scale stock, a rotatable protractor ring and supporting means therefor on and adjustable along the scale beam, a three-cornered rule extending across and supported by the ring, and rotatable therewith, one edge of the rule being located in a diameter of the ring, said rule having its supports in the ring in the form of pivots for rotation of the rule about its longitudinal axis to present any one of its edges in the diameter of the ring, and a latch device on the ring for engaging the rule and holding it in any one of its positions of adjustment about its longitudinal axis.

8. A drafting instrument comprising a scale stock, a scale beam supported at right angles to and adjustable along the scale stock, a rotatable protractor ring and supporting means therefor on and adjustable along the scale beam, a three-cornered rule mounted at the ends in the ring and rotatable with the ring, said rule being also rotatable about its longitudinal axis and located with respect to the ring to have any one of the edges of the rule located in a diameter of the ring, and a holder for a marking implement mounted on the rule for movement lengthwise thereof.

9. A drafting instrument comprising a scale stock, a scale beam supported at right angles to and adjustable along the scale stock, and a protractor mounted on and adjustable along the scale beam, said protractor comprising a supporting ring and other independently rotatable rings carried by the supporting ring, one of the rotatable rings being provided with a rule extending across and rotatable with it and located with respect to the ring to have an edge in a diameter of the ring.

10. A drafting instrument comprising a scale stock, a scale beam supported at right angles to and adjustable along the scale stock, and a protractor mounted on and adjustable along the scale beam, said protractor comprising a supporting ring and other independently rotatable rings carried by the supporting ring, one of the rotatable rings being provided with a rule extending across and rotatable with it and located with respect to the ring to have an edge in a diameter of the ring, said rule being rotatable

about its longitudinal axis and provided with a plurality of scales and edges, whereby any one of the edges having a scale associated therewith may be located in the 5 said diameter of the ring.

11. A drafting instrument comprising a scale stock, a scale beam supported at right angles to and adjustable along the scale stock, and a protractor carried by the scale beam and movable therewith, said protractor comprising a supporting ring and other rings mounted thereon for rotation thereabout, said other rings having scales thereon, and means for holding each rotatable ring in an adjusted position for independently holding the rotatable ring in its adjusted position.

12. A drafting instrument comprising a scale stock, a scale beam supported at right angles to and adjustable along a scale stock, and a protractor mounted on and adjustable along the scale beam, said protractor comprising a supporting ring, another ring mounted on and rotatable with respect to the supporting ring and provided with a rule extending across said rotatable ring with one edge of the rule in a diameter of the ring, and means for holding the rotatable ring in different positions of adjustment, comprising a clamp bolt with a manipulating portion for rotating the ring and a clamp member on the clamp bolt for binding the ring in different positions of adjustment.

13. A drafting instrument, comprising a scale stock, a scale beam supported at right angles to and adjustable along the scale stock, and a protractor mounted on and adjustable along the scale beam, said protractor comprising a supporting ring, a scale ring rotatably mounted on the supporting ring, another scale ring rotatably mounted on the supporting ring, means for releasably holding the first-named scale ring in adjusted positions on the supporting ring, and means for releasably holding the second-named scale ring in adjusted positions on the supporting ring.

14. A drafting instrument comprising a scale stock, a scale beam supported at right angles to and adjustable along the scale stock, and a protractor mounted on and adjustable along the scale beam, said protractor comprising a supporting ring, a scale ring rotatably mounted on the supporting ring, another scale ring rotatably mounted on the supporting ring, means for releasably holding the first-named scale ring in adjusted positions on the supporting ring, and means for releasably holding the second-named scale ring in adjusted positions on the supporting ring, the means for releasably holding the second-named scale ring in adjusted positions including a manipulating member and a clamp member.

15. A drafting instrument comprising a scale stock, a scale beam supported at right angles to and adjustable along the scale stock, and a protractor carried by and adjustable along the scale beam, both the scale beam and the protractor having temporarily acting stop means each movable in a direction transverse to the direction of adjustment.

16. A drafting instrument comprising a scale stock, a scale beam supported at right angles to and adjustable along the scale stock, and a protractor carried by and adjustable along the scale beam, an indicating means on both the scale beam and protractor, said indicating means comprising a spring finger for engaging the scale beam or scale stock, as the case may be, a carrier for the spring finger, and a support for the carrier extending crosswise of the direction of movement of the scale beam or protractor, as the case may be, for adjustment of the spring finger into operative relation to different scales on the scale stock or scale beam.

17. A drafting instrument comprising a scale stock, a member mounted on and slidable along the scale stock and including a block having grooves and ribs extending crosswise of the length of the scale stock, and a scale beam having one end forked and provided with flanges and grooves adapted to fit the flanges and grooves of the block, whereby the scale beam may be applied to or removed from the block and when applied thereto be in right angular relation to the stock.

18. The combination with a drafting board, of supporting members secured to one edge of the board near the ends thereof, a scale stock pivotally connected to the supporting members at the ends of the scale stock and at a lower level than the working surface of the drafting board, a member slidable lengthwise of the scale stock and rising higher than the working surface of the drafting board, a scale beam mounted on the carrying member and extending at right angles thereto over the working surface of the drafting board, a carrying member on the scale beam, a protractor on the carrying member extending over the working surface of the drawing board.

19. The combination with a drafting board, of supporting members secured to one edge of the board near the ends thereof, a scale stock pivotally connected to the supporting members at the ends of the scale stock and at a lower level than the working surface of the drafting board, a member slidable lengthwise of the scale stock and rising higher than the working surface of the drafting board, a scale beam mounted on the carrying member and extending at right angles thereto over the working surface of the drafting board, a carrying member on the scale beam, and a protractor on

the carrying member extending over the working surface of the drawing board, said protractor having portions extending below the level of the surface toward the drawing board to engage paper mounted on the drawing board and thereby hold the protractor and the scale beam from engagement with said paper.

In testimony, that we claim the foregoing as our own, we have hereto affixed our signatures in the presence of two witnesses.
